UNITED STATES PATENT OFFICE.

JOHN P. CRANE, OF INDIAN ORCHARD, MASSACHUSETTS.

DOFFING DEVICE FOR SPINNING-MACHINES.

1,252,404.

Specification of Letters Patent. Patented Jan. 8, 1918.

Application filed May 17, 1917. Serial No. 169,233.

To all whom it may concern:

Be it known that I, JOHN P. CRANE, a citizen of the United States of America, residing in Indian Orchard, in the county of 5 Hampden and State of Massachusetts, have invented certain new and useful Improvements in Doffing Devices for Spinning-Machines, of which the following is a specification.

10 This invention relates to improvements in attachments to spinning machines, such attachments being known as "doffing" devices for simultaneously removing all of the filled bobbins from the spindles and for simultaneously replacing all of the empty bobbins or spools on the winding spindles. A common practice, at the present time, is to manually remove the filled bobbins, one by one from the spindles, which operation 15 necessitates shutting down the machine for a considerable period, not only while the filled bobbins are being removed but also while the empty bobbins are being put in place on the spindles.

20 My invention, broadly considered, comprises a frame work which extends the length of the machine and is adapted to be operated by suitable means, preferably located at one end of the machine for removing the filled bobbins. This framework includes a bar formed with openings, which bar is designed to be slipped down over the filled bobbins and is provided with suitable means for engaging or gripping the bobbins 25 to simultaneously effect the lifting of all of them free from the spindles and into a position that is out of the path of the empty bobbins, which at this point, in the operation, are lowered past the filled bobbins and 30 into position on the driving spindles. Suitable devices are provided for simultaneously releasing all of the filled bobbins, permitting the same to fall by gravity into a suitable receptacle. The apparatus which is used to 35 place the empty bobbins is first raised into its initial position after the operation of removing the filled bobbins has taken place.

40 Referring to the drawings:

45 Figure 1 is a side elevational view showing the two frames for removing the filled bobbins and for replacing the empty ones, with means for operating the same during the removal and filling operations;

50 Fig. 2 is an end elevational view of Fig. 1 looking from the right of this figure and

showing the devices for operating the frame which removes the filled bobbins and the cords which control the frame and which carry the empty bobbins;

55 Fig. 3 is an enlarged end elevational view looking from the left of Fig. 1, as indicated by the arrow and clearly showing the rack and pinion construction which is operated by the hand wheel that controls the up and down movements of the frame for taking off the filled bobbins, and also the hand wheel which controls the movements of the frame for lowering the empty bobbins into place on the spindles;

60 Fig. 4 is a partial transverse sectional view on the line 4—4 of Fig. 1 showing the position of the attachments before the filled bobbins are removed and before the empty bobbins are lowered, also illustrating one hand wheel for operating the cables which 65 controls the means for replacing the empty bobbins;

70 Fig. 5 is a view similar to Fig. 4 showing the bobbin removing frame after it has just been lowered to engage the filled bobbin; 75 the gripping devices for engaging the filled bobbins being shown in contact therewith;

80 Fig. 6 is a view similar to Fig. 4 and which might properly be termed the third position in the operation of removing the 85 filled bobbins, which shows the filled bobbins swinging into the dotted line position;

85 Fig. 7 illustrates the position of the empty bobbins after they have been lowered into engagement with the spindles and the position that the bobbin-releasing device assumes to free the filled bobbins from the 90 bobbin removing frame;

95 Fig. 8 is a detail end view of a portion of the shaft which supports the bobbin-removing frame and illustrating the hexagonal nut in section which is engaged by a wrench, or other device for operating the shaft for swinging the filled bobbins into the position shown in Fig. 6 and prior to the removal, 100 as shown in Fig. 7;

105 Fig. 9 is a detail view of the rail or rod which carries the clips which temporarily retain the empty spindles in place.

Referring to the drawings in detail: 1 and 110 2 designate the end frames of the machine which are provided with the slideable racks 3 and 4 which are movable up and down as will be described. These racks are engaged by the pinions 5 and 6 that are mounted on

the ends of a transversely located shaft 7 the center portion of which is provided with a spiral thread 8, which thread is engaged by a spiral gear 9, whereby when the hand wheel 10 is operated the shaft 7 will be rotated causing the pinions to raise or lower the racks 3 and 4, depending upon the direction of rotation of the wheel 10. Extending longitudinally of the machine is a shaft 11 which carries a spiral gear 12 at its opposite end which in turn, meshes with the spiral gear 13 and which operates correspondingly located racks at the other end of the machine for raising and lowering the bobbin removing frame. Attached to these racks are the bars 14 having the openings 15 therein. Normally, or while the thread is being wound on the bobbins, these bars are held in an elevated position as shown in Figs. 2, 3, and 4. Attached to these bars are the manually operable levers 16 and movable by the levers is the rod 17 which carries the fingers 18 which engage the filled bobbin. The bars 14 are attached to movable links 19 by means of the brackets 20. The upper ends of the links 19 are pivotally connected to a shaft or rod 21 that extends longitudinally of the machine as shown clearly in Fig. 1, in side elevation, and in Figs. 2, 3, 4, in end view. These shafts travel up and down in the longitudinal openings 22 of the end frames, when removing the filled bobbins or lowering the bobbin removing frame. When it is desired to remove the filled bobbins, which are indicated in Figs. 4 and 5 at 23, the operator rotates the hand wheel 10 causing the racks 3 and 4 to descend, which carry the bars 14 therewith. The openings 15 in the bars 14 pass down over the filled bobbins, as indicated in Fig. 5. The operator then moves the lever 16 toward the right causing the fingers 18 to engage the filled bobbin, as shown in Fig. 6. The operator now moves the lever 16 to bring the fingers 18 into contact with the threads of the filled bobbins to grip the same. Upon the rotation of the hand wheel 10 in the opposite direction the bar 14 will be elevated carrying with it all of the filled bobbins 23 as indicated in Fig. 6. After the bobbins have been elevated above the spindles 24, the operator now moves the bar 14 outward by applying a wrench or other implement to the nut 24' on the end of the shaft 21, from the position shown in Fig. 6 to that shown in Fig. 7 in which position the bar is held or supported by means of the link 25 which is connected to the link 19, this link 25 is placed by the operator in a socket in the plate 26, as shown. The next step in the operation is replacing the empty bobbins or spools on the spindles 24 and this is accomplished as follows: The operator places the empty bobbins, as shown in Figs. 3, 4, and 5, in the

spring clips 28, one of which is shown in plan view in Fig. 9 which comprises spring metal, the throat portion of which is narrower than the diameter of the spool. These clips which correspond in number to the 70 number of the spindles 24 are all attached to a rod 29 which extends the length of the machine. This rod is supported at its ends by means of the cable 30 on the outside of the end frames and over the drums 31 and 32 75 at the opposite sides of the machine and then downward over the rollers 33 and 34 and the winding drums 35 and 36 which are located, as shown in Fig. 1, at the opposite ends of the machine. These drums 80 35 and 36 are operated by the hand wheel 37 by means of the longitudinally arranged connecting shaft 38. As the hand wheel 37 is rotated the empty spools or bobbins are lowered in position to slip on to the winding 85 spindles 24 (see Fig. 7). It will be noticed that the drums 31 are connected to shafts 31' which extend through the end frames 1 and 2 and to the inner ends of which drums 31' are attached. 90

In order to free the bobbins 27 from the spring clips 28 after the empty bobbins have been placed on the spindles 24 the operator pulls outward on the rod 29 in the direction of the arrow 31², as shown in the dotted line 95 position 29', Fig. 7, thereby freeing all of the empty bobbins from this rod. The next step is to disengage the filled bobbins 23 from the bobbin removing bar 14. This is accomplished by the operator pulling toward 100 the left on the lever 16, (Fig. 7), whereby the fingers 18 are simultaneously disengaged from the filled bobbin allowing them to fall into the receptacle 39, shown in Fig. 7.

It should be stated that after the rod 29 105 is freed from the empty bobbins the hand wheel 37 is again operated and the rod is drawn upward to its initial position in the upper part of the machine. The racks 3 and 4 are also moved upward into the position shown in Fig. 3 which places them ready for the next operation of removing the filled bobbin as already described. 110

The usual drawing rollers are indicated in Figs. 4 and 5, at 40, from which extends 115 the threads to the bobbins being wound. The steps or positions may be summed up as follows: first, that shown in Fig. 4 where the bobbins are filled. The bobbins are filled ready to be removed, the bobbin removing rail being in elevated position as shown in this figure. In the second position the rail 14 has been lowered as shown in Fig. 5 and slipped over the filled bobbins. The lever 16 is now operated to move the 120 finger 18 into contact with the filled bobbin. In the third position shown in Fig. 6, the operator now operates the hand wheels 10 causing all of the filled bobbins to be drawn 125 upward above the spindle 24, next the op- 130

erator rotates the shaft 21 by means of a wrench or other implement which is placed on the nut end 24, and swings the bar 14 and the filled bobbins to the dotted line position where it is temporarily elevated until the empty bobbins are placed on the spindles 24. In the fourth position the operator rotates the hand wheel 37 for lowering the bobbins 27 into the position shown in Fig. 7, then he pulls outward on the rod 29 freeing the bobbins from the spring clips 28. The rod 29 is then drawn upward again into its initial position for the operator to fill the spring clips 28 with empty bobbins. Next the operator moves the lever 16 outward thus releasing the gripping fingers 18 from the filled bobbins whereby they will fall into a receptacle 39 which is placed along the side of the machine. The braces 25 are then released and the frame drawn upward again into the position shown in Fig. 4 where it is ready for the next operation of doffing the filled bobbins.

What I claim is:

1. In a doffing device for spinning frames the combination with a vertically movable bar formed with openings therein to receive the filled bobbins, means for moving the bar to cause the openings therein to pass over the filled bobbins, means for gripping the bobbins when the bar is in this position, means for elevating the bar and bobbin as a unit, devices for swinging the bar and bobbins outward to a position beyond the plane of the end of the frame of the machine prior to disengaging the bobbins, a bar provided with spring clips for temporarily receiving the empty bobbins, means for lowering this bar positioning the empty bobbins on the spindles, the empty bobbins being released from the bar by an outward pull thereon, and means for disengaging the filled bobbins from the first mentioned bobbin receiving bar, as described.

2. In a doffing device for spinning frames for removing the filled bobbins and for replacing the empty bobbins, said device comprising a bar formed with openings therethrough for receiving the filled bobbins, means for gripping the filled bobbins, devices for elevating the bar and bobbin into a position above the winding spindles, means for moving the filled bar and bobbins in a lateral direction away from the vertical axis of the winding spindles to permit an empty bobbin holder to be lowered in position on the spindles, means for supporting the empty bobbins, and means for raising and lowering said empty bobbin-supporting means.

3. In a doffing device the combination with the end frames of the spinning machine, recesses in the ends of the frame, racks located therein, means for operating the racks, a filled bobbin receiving bar

secured to the racks for raising and lowering the bar into a position over the filled bobbins, means on the bar for gripping the filled bobbins to effect their removal from the spindles when the bars are elevated, and means for releasing the filled bobbins when the gripping means is moved in an opposite direction, as described.

4. In a spinning frame, the combination with the spindles thereof, of means for placing the empty bobbins on the spindles, including a bar provided with spring clips for releasably holding the empty bobbins in place thereon, a shaft extending longitudinally of the machine and having cable winding drums on its ends, cables extending from the drums and connected to the empty bobbin-supporting bar, whereby when the shaft is operated the empty bobbins will be lowered into position for placing empty bobbins on the winding spindles, said bobbins being simultaneously removed from the clips by a pull in a direction transverse to the axis of the winding spindles.

5. In a doffing device the combination with a spinning frame, the end plates of which are formed with longitudinal openings, racks in the openings, a shaft secured to the racks and traveling therewith and having its ends formed with a projection to receive a suitable implement for rotating the shaft, a link secured to the shaft, a bobbin receiving bar secured to the link and formed with openings therein and designed to slip over the filled bobbins, means engaging the rack for elevating the bobbins and removing them from the spindles, the rotation of said shaft serving to move the bobbins to a position beyond the plane of the end frames, and means for releasing the filled bobbins, comprising gripping fingers for engaging the filled bobbins.

6. In combination with the winding spindles of a spinning frame, of means for replacing the empty bobbins on said spindles, comprising a bar, spring clips secured thereto for temporarily receiving the empty bobbins, cables secured to said bar, drums located on the inside of the end frames, and to which the cables are secured, shafts secured to said drums and arranged near the top of the end frames, drums on the outer ends of the shaft, cables secured to the drums and secured to a winding drum, whereby the empty bobbins can be lowered by the operation of the winding drums and into a position to permit the empty bobbins to be placed on the spindles, said clips permitting the bobbins to be removed therefrom when moved in a direction transversely to the machine.

7. In a device for holding the empty bobbins in a spinning machine prior to placing them on the winding spindles and comprising a member to which clips are secured the

clips having a throat portion that is narrower than the seat-receiving portion to permit their insertion, and to permit their removal when the member is moved in a direction that is transverse to the machine, 5 means for raising and lowering the bar, comprising winding drums and cables which

are attached to the bar, said cables permitting the bar to be swung outward after the empty bobbins have been placed on the winding spindles, whereby the empty bobbins are disengaged from the bar and positioned on the winding spindles. 10

JOHN P. CRANE.
